PAIR OF SPECTACLES FOR EYE MAKE-UP

Charles Baratelli, Reading, Pa., assignor to Gladys W. Holloway, Los Angeles, Calif.

Filed July 25, 1961, Ser. No. 66,057

Term of patent 14 years

(Cl. D57—1)

FIG.1

FIG.2

FIG. 3

FIG. 4

FIG. 5

FIG. 1 is a reduced scale perspective view of a pair of spectacles for eye make-up showing my new design;
FIG. 2 is a full scale top plan view thereof;
FIG. 3 is a full scale side elevational view thereof;
FIG. 4 is a full scale front view thereof; and
FIG. 5 is a full scale rear view thereof.

I claim:

The ornamental design for a pair of spectacles for eye make-up, substantially as shown.
